UNITED STATES PATENT OFFICE.

NORDAHL O. NELSON, OF WESTBY, WISCONSIN.

BRACE FOR CABINETS.

1,130,426.

Specification of Letters Patent.

Patented Mar. 2, 1915.

Application filed November 12, 1914. Serial No. 871,767.

To all whom it may concern:

Be it known that I, NORDAHL O. NELSON, a citizen of the United States, residing at Westby, in the county of Vernon and State 5 of Wisconsin, have invented certain new and useful Improvements in Braces for Cabinets, of which the following is a specification, reference being had therein to the accompanying drawing.

10 This invention relates to braces for cabinets and has for its principal object the production of a brace which may be easily adjusted for conforming to the shape of a bracket or plurality of sections of an assembled device for efficiently securing the sections together to constitute a one-piece structure.

Another object of this invention is the production of a brace for cabinets which 20 comprises a plurality of brackets to which tie rods are secured in such a manner as to efficiently bind a plurality of sections of a structure in engagement with each other and which is so formed as to conform in 25 contour to the shape of the assembled structure.

Still another object of this invention is the production of a brace for cabinets comprising a plurality of angular brackets 30 which are adapted to be carried at the abutting ends of a plurality of sections and which are adapted to carry a plurality of tie rods so as to efficiently bind the plurality of sections of a structure in engagement 35 with each other and allow the structure to constitute a substantially one-piece structure of a desired shape.

With these and other objects in view this 40 invention consists of certain novel combinations, constructions, and arrangements of parts as will be hereinafter fully described and claimed.

In the accompanying drawings:—Figure 1 is an elevation of a figure representing a 45 bar showing the brace in dotted lines illustrating the manner in which the device is used. Fig. 2 is a detailed perspective view of a plurality of sections showing the brackets and tie rods in perspective and 50 illustrating the manner in which the same are used for holding the sections in an assembled position. Fig. 3 is a fragmentary plan view of the abutting ends of a plurality of sections illustrating the manner in 55 which the brackets and tie rods secure the sections together, the sections being pro-

vided with slightly modified inner ends. Fig. 4 is a detailed perspective view of one of the angular brackets. Fig. 5 is a detailed perspective view of a slightly modified form of the bracket. Fig. 6 is an elevation of a structure representing a barber's wall case and showing the brace member in dotted lines, illustrating the manner in which the same is used. Fig. 7 is a central vertical section taken through the device as disclosed in Fig. 6. Fig. 8 is a top plan view of a plurality of sections secured together to form a column or like structure of octagon shape. Fig. 9 is a top plan view of a plurality of sections secured together by means of a brace to form a round column. Fig. 10 is a vertical section through a modified form of the bracket illustrating how the same is used in the construction of a 75 counter. Fig. 11 is a detailed perspective view of the bracket as disclosed in Fig. 10. Fig. 12 is an elevation of another form of the bracket used for connecting a plurality of sections. Fig. 13 is a sectional view 80 through a form of a nut and bur which may be used in connection with this invention for adjusting the tie rods. Fig. 14 is a detailed perspective view of one of the angular brackets showing the nut and adjustable 85 bur carried thereby. Fig. 15 is a detailed perspective view of another form of the angular bracket. Fig. 16 is a detailed perspective view of still another form of the angular bracket. Fig. 17 is a detailed perspective view of the supporting bracket which is adapted to be used in connection with this invention. Fig. 18 is a detailed perspective view of a slightly modified form of a supporting bracket. Fig. 19 is a transverse section through the connecting brackets showing the manner in which the brackets are anchored together.

Referring to the accompanying drawings by numerals 1 designates the angular bracket which is preferably L-shaped and through which there extends a plurality of transverse apertures 2. The body 1 is provided at its inner portion with the reinforcing web 3 and upon its outer edge with the integral ribs 4 extending therearound. There is also formed integral upon the side of the body 1 at a spaced distance from the outer front edge of the ribs 4 the lateral projection 5 through which the screws 6 may pass for holding the bracket in engagement with the support. By referring to Fig. 2 it

will be seen that the sections 7 have grooves 8 formed at their abutting ends for the reception of the ribs 4 of the angular brackets. Two of these brackets are adapted to 5 be positioned adjacent each other owing to the fact that a bracket is carried by each abutting end of each section 7. The tie rods 9 are positioned so as to span the longitudinal length of each section 7 and pass 10 through the transverse apertures 2 formed in the bodies 1 of the angular brackets and extend through these apertures so as to carry the nuts 10. In order to brace the angular brackets which are carried by the 15 end sections 7 these end sections may also be provided with ears 11 through which the tie rods 9 may pass and be secured in the usual manner. By referring to Fig. 2 it will be seen that after the tie rods have 20 been passed through the angular brackets the nuts may be adjusted so as to hold the abutting end portions of the sections 7 tightly in engagement with each other while the rods span the longitudinal length of 25 the sections. In this manner the sections may form a substantially one-piece structure since the brackets are held upon the end portions of the sections by means of the screws 6 while the tie rods 9 pass 30 through the angular brackets for holding the same in engagement with each other thereby binding the sections in engagement to form a one-piece structure.

By referring to Fig. 1 it will be seen that 35 the bar 12 has columns 13 at its ends which support the cabinet top 14. It will be seen that the tie rods and brackets are shown in dotted lines for holding this cabinet top to form a substantially one-piece construction to be supported by the columns 13. In 40 this figure and also by referring to Fig. 2 it will be seen that the apertures 2 will allow the tie rods 9 to be adjusted so as to converge when necessary to take up the slack 45 in each rod which may be produced owing to the length of the sections which are secure. Plates as shown at 15 may be positioned at the end portions of the cabinet top to which the cross tie rods 9' are attached 50 so as to efficiently brace the end portions of the cabinet top.

By referring to Fig. 6 it will be seen that the brace may also be used for holding the sections of a barber's wall cabinet together. 55 16 designates the ordinary article holders of the barber's wall cabinet which are supported by the angle bars 17. These angle bars 17 carry face plates 18 and extend to the top sections 19. These top sections 19 60 are adapted to carry the angular brackets to which the tie rods 9 are secured. These tie rods 9 in this use may also extend in parallel spaced relation or in converged relation to efficiently bind the upper portions 65 of the wall cabinet together and therefore

when the nuts have been adjusted the wall cabinet will be held efficiently in a fixed set up position to constitute a one-piece structure.

In Fig. 3 it will be seen that the sections 7' may be provided with grooves 8' at a spaced distance from the abutting ends of the sections 7' thereby forming shoulders 8''. The ribs 4 of the angular brackets 1 are adapted to fit in these grooves so as to 75 allow the brackets to remain in engagement with the sections and allow the shoulders 8'' to partially relieve some of the strain from the securing screw 6 and the tie rods 9.

In Fig. 5 an angular bracket is produced which comprises a substantially U-shaped body 20 having an internal web 21 and outer integral ribs 22 and this body 20 is also provided with transverse openings 23 through which the tie rods 9 may extend when this form of the bracket is used. This bracket may be used when a plurality of sections are adapted to be connected which present a square body instead of the construction as disclosed in Fig. 2.

In Figs. 8 and 9 it will be seen that the sections 24 and 25 respectively may be placed so as to allow their abutting ends to engage each other. In Fig. 8 the device is 95 used to construct an octagon column at which time the beveled end 26 will carry the angular brackets 1 while the tie rods 9 will be secured at the outer portions of a 100 pair of the angular brackets and then converge to be secured to the central portion thereof. In this manner the extra length of the tie rods will be taken up. The sections 25 of Fig. 9 carry the angular brackets at their abutting ends to which the tie rods 105 9 are secured. In this construction the brace is used for holding in an assembled position a plurality of sections used for forming a round column. In order to take up the extra length or slack in the tie rods 110 it will be necessary to cross the tie rods as disclosed in dotted lines in Fig. 9. In this case one tie rod will extend from the outer portion of a pair of the angular brackets and will extend inwardly toward the inner 115 portion of the next adjacent bracket. The other tie rod will be secured adjacent the inner portion of the first mentioned angular brackets and will then extend outwardly across the other tie rod to be secured to the outer portion of the next adjacent bracket.

By referring to Figs. 10 and 11 it will be seen that another form of angular brackets has been produced for supporting counters and like structures. In this case the brackets constitute one-piece bodies 27 having the ribs 28 upon their outer portions and the integral lips 29 extending so as to be secured to the boards which are used to construct the counter. A leg 30 is formed integral upon 125 130

the upper portion of the bracket 27 and is braced by the bar 31. It will be seen that the lips 29 are provided with apertures 32 through which suitable securing means may 5 be passed to attach the bracket to the end of one of the sections. The tie rods may then be passed through the ribs 28 for positively retaining a plurality of sections of a counter in engagement with each other to 10 form a one-piece structure. This bracket is provided with the offset portions 33 for allowing the counter to assume the usual shape.

By referring to Fig. 12 it will be seen that 15 another form of the angular bracket has been produced which constitutes a one-piece structure 34. From this one-piece structure there extends the ears 35 through which securing means 36 may be passed for positively 20 retaining the angular brackets in engagement with the sections 7. The tie rods 9 may be passed through the one-piece bracket 34 and the nuts 10 may be threaded in engagement with the tie rods for positively 25 retaining the sections of the device together.

By referring to Figs. 15 and 16 it will be seen that another form of the angular brackets has been produced in which the bodies 37 and 38 have transverse apertures 39 for the passing of the tie rods therethrough while the body 37 is provided with an integral brace finger 40 for reinforcing the same.

35 In Figs. 17 and 18 other forms of supporting brackets have been produced and in these figures the body 41 has apertures 42 for the reception of securing means and a brace finger 43 for reinforcing the same 40 while the body 44 has a short lip 45 and an enlarged brace 46. These devices as disclosed in Figs. 17 and 18 are adapted to fit in the corners of the structure for holding the same in its correct position.

45 From the foregoing description it will be seen that a simple and efficient brace having any desired shaped structure has been produced which is so formed as to engage the end portions of a plurality of sections and 50 carry a plurality of tie rods whereby the tie rods may be adjusted to secure the brackets in their correct position for retaining the sections in engagement with each other to constitute a one-piece structure.

55 By carefully considering Figs. 13 and 19 it will be seen that the bracket portions 1 are provided with threaded apertures 2^a into which the hollow externally threaded plugs 3^a are threaded. A pin 4^a is carried 60 by the adjacent bracket and is adapted to have its projecting end fit into the socket formed in the hollow plug 3^a for anchoring the adjacent brackets together so as to hold

the respective apertures 2 in proper alignment to allow the rods 9 to pass there- 65 through.

What I claim is:—

1. In a device of the class described the combination with a plurality of sections, said sections provided with grooves adjacent their end portions, angular brackets carried by said sections and partially fitting within said grooves, lateral projections formed integral upon said brackets, means for securing said lateral projections to said sections and tie rods spanning said sections and engaging said brackets for holding said sections in engagement with each other thereby forming a one-piece structure.

2. In a device of the class described the combination with a plurality of sections having grooves adjacent their end portions, angular brackets carried by said sections and partially fitting within said grooves, said brackets provided with a plurality of 85 transverse apertures, a plurality of tie rods spanning said sections and passing through said apertures, a plurality of said rods converging toward each other, to accommodate different sized sections and take up the slack 90 in the tie rods whereby the sections will be held in engagement with each other to form a one-piece structure.

3. In a device of the class described the combination with a plurality of sections, 95 having grooves adjacent their inner portions, angular brackets carried by said sections, said brackets provided with ribs upon their outer portions, said ribs fitting within said grooves, said brackets provided with 100 transverse apertures, tie rods passing through said apertures and spanning the distance between said brackets, said tie rods being adapted to be secured in position so as to allow said sections to be held in engagement with each other to form a one-piece structure.

4. A device of the class described comprising a plurality of brackets arranged in close proximity, each bracket provided with 110 a plurality of threaded apertures, one of said brackets provided with hollow threaded plugs threaded into the apertures formed therein, the other of said brackets provided with lugs threaded into the apertures 115 formed therein and adapted to project from one side thereof, and the plugs of one bracket fitting in the socket plugs of the other bracket for firmly anchoring said brackets together.

In testimony whereof I hereunto affix my signature in presence of two witnesses.

NORDAHL O. NELSON.
